UNITED STATES PATENT OFFICE.

GUIDO FORNACA, OF TURIN, ITALY, ASSIGNOR TO F. I. A. T., A CORPORATION OF NEW YORK.

COMBUSTION-ENGINE.

1,190,255.

Specification of Letters Patent. Patented July 4, 1916.

Application filed November 18, 1913. Serial No. 801,585.

To all whom it may concern:

Be it known that I, GUIDO FORNACA, a subject of the King of Italy, residing at Turin, in the Province of Piedmont, Italy, have invented certain new and useful Improvements in Combustion-Engines, of which the following is a full, clear, and exact specification.

This invention relates to a six cylinder engine casting and has particular reference to the construction and arrangement of the cylinders, the gas inlets and outlets, and the water passages whereby a compact light and strong six cylinder engine is made in a single casting.

I have heretofore invented four cylinder block motor castings, wherein the water jacket incloses the inlet and exhaust manifolds and also embodying the removable cover, which have been successfully operated. So far as I am aware, however, prior to the invention of this application, six cylinder motors have been built up of separate castings, each casting embodying one or 25 more cylinders with outside connections for the manifolds and the water circulation, it having been considered impracticable to embody six cylinders in a unitary casting and at the same time to provide for the 30 necessary mechanical strength, equal water circulation, equal distribution of charge to the various cylinders, and substantial equalization of temperature throughout the casting. By this invention, I have succeeded in 35 attaining these objects, and have produced a six cylinder block motor having considerably less weight and length for the same power, as compared with six cylinder motors built up of several castings, and without 40 the production of objectionable strains, insufficient water circulation or unequal distribution of charge to the cylinders. I am also enabled to simplify the external ap- 45 purtenances of the motor and to inclose all moving parts, so that utmost quietness in operation is attained.

In the preferred form of this invention, the admission and exhaust valves and passages are located on the same side and with- 50 in the water jacket in a very compact manner, providing equal distribution of gases and strains due to heating, while permitting proper water flow and efficient cooling. An engine of minimum dimensions and 55 weight in proportion to its power is pro-

vided, and in which all working parts can be easily inclosed.

In accordance with this invention, the cylinders are divided into groups of two cylinders each, and the admission passage 60 or passages are arranged to distribute uniformly the explosive mixture to the several cylinders of the six cylinder engine. The cylinders of each pair have in part common wall portions, whereby the cylinders of the 65 respective pairs are brought closely together, and the entire casting shortened and lightened as compared with engines built up of several cylinders or separate groups. The admission passage comprises two trans- 70 verse main passages connected to a common longitudinal passage, within the water jacket, the inlet valve chambers opening from this longitudinal passage and all being at substantially the same distance from 75 the supply. The exhaust passage is also embodied in the casting, so as to be cooled by the water and thereby prevent injurious or dangerous strains.

Other objects and advantages of the invention will be more fully understood from the following description, and the accompanying drawings, in which—

Figure 1 is a sectional elevation of a six cylinder engine embodying the invention, 85 on the line 1—1 of Fig. 3; Fig. 2 is a longitudinal section on the line 2—2 of Fig. 3; Fig. 3 is a horizontal section taken on the line 3—3 of Fig. 1; Fig. 4 is a horizontal section taken on the line 4—4 of Fig. 1; Fig. 90 5 is a horizontal section taken on the line 5—5 of Fig. 1; Fig. 6 is a vertical section taken on the line 6—6 of Fig. 3; Fig. 7 is a vertical section taken on the line 7—7 of Fig. 3; and Fig. 8 is a vertical section taken 95 on the line 8—8 of Fig. 3.

1 represents the base upon which the casting is mounted in the vehicle, which is of usual and well known construction. The casting is made up of cylinders 2, 3, 4, 5, 6 100 and 7, each of which has an integral head, and is opened at the bottom. The cylinders 2, 3 are joined so as to have a common wall 13, with corresponding wall 14 for cylinders 4, 5, and corresponding wall 15 for cylinders 105 6, 7. This avoids spaces between the cylinders as heretofore employed in six cylinder engines, enabling the over-all length of the engine to be considerably reduced, and also assists the flow of water as will be more 110

fully explained. 28 is a water jacket integral with the cylinders and surrounding the tops and heads thereof, the top of the water jacket being preferably open to receive a removable cover 8, which is suitably bolted thereto. The cover 8 is provided with a channel 35 which discharges the water to the cooler through outlet 36, and receives the water from the water jacket 28 through cover inlet or water jacket outlet 37. The water is admitted to the water jacket at the front lower side through inlet 38, preferably from a pump, and must be equally distributed around the sides and heads of each of the cylinders, and around the inlet and exhaust manifolds, so as to keep the interior of the casting at a practically uniform temperature to avoid injurious strains due to unequal expansion, and also so that one cylinder will not be any cooler than another. In order to do this a system of baffles and water guides is provided which not only guide the flow of water but connect the interior parts of the casting to the water jacket and cylinder, so that the entire structure is properly supported and interiorly braced. The water is also caused to flow in such manner as to be aided by convection and to avoid slack water pockets, or eddies. It is impossible to show all of the baffles in any one figure, but Figs. 1, 2 and 5 show a number of them. Adjacent the head of each cylinder are vertical baffles 40, which are extended to form external ribs 41 on the cylinder heads, which not only strengthen the heads to resist the explosion, but guide the water vertically upward and over each cylinder head, it being seen that there is a space provided immediately below the lower surface of the cover 8 through which the water can flow horizontally above the cylinder heads to the water jacket outlet 38. There are also vertically disposed side baffles 42 between each cylinder and the water jacket so that the water is caused to flow vertically up and over the center of each cylinder head. There are also two or more vertical baffles 43 between the water jacket 28 and the exhaust manifold 25 which also direct the water upward, and tend to break up the natural longitudinal flow between inlet 38 and outlet 37. Between the separated cylinders 3, 4 and 5, 6, vertical baffles 45 are provided, for the purpose of directing the flow of water upwardly between these cylinders, and also to support the inlet pipes 16, 17. By this arrangement of the inlet at the end of the water jacket and the outlet at the opposite upper end, the water will be broken up into parallel upwardly flowing currents, which will merge in the space above the cylinder heads and flow toward the outlet. It will also be seen that the natural upward convection currents caused by the heating of the water will assist the

forced flow, while slack water pockets or eddies will be avoided.

While reduction of over-all length of the casting and vertical flow of water are facilitated by making pairs of cylinders tangent to each other with a portion of their walls common, the pairs of cylinders are preferably spaced to receive the transverse inlet pipes 16, 17. These pipes extend transversely of the casting from one side and are externally connected through a Y to the carbureter. In order to secure uniform temperature and equal distribution of the inlet gases to each of the six cylinders in its proper turn, and also to avoid unnecessary width of the casting, a special arrangement of the inlet and exhaust manifolds and their connections with the several valve chambers is provided. The pipes 16, 17 are shown in section in Fig. 4, in which it will be seen that they respectively connect with closed end pipes 21, 23, and are connected to each other at the opposite side of cylinders 4 and 5. The inner walls of pipes 16 and 17 being in part common with the walls of cylinders 3, 4, 5 and 6, enables the inlet manifold composed of the three sections 23, 18, 21, to be very short, and to be brought very close to the cylinders without undue increase of width of the entire casting. It also insures a uniform heating of the mixture, which is heated by the water upon entering pipes 16 and 17, and then passes very close to the cylinder interiors. It will also be seen that each cylinder will be practically the same distance from the carbureter, which is essential in order that each will obtain the same supply of gas, and also secures a considerably shorter path of the gas than is provided for in previous six cylinder engines built up of separate castings.

The inlet gas passage 23 opens into a double inlet chamber 24 supplying cylinders 2 and 3, while inlet passage 18 opens into a double chamber 20 supplying cylinders 4 and 5, and passage 21 opens into a similar double inlet chamber 22 supplying cylinders 6 and 7. These openings appear as narrow slots immediately inside the sectioned upper sides of inlet chambers 24, 20 and 22 in Fig. 3, but it will be seen from Fig. 7 that they are inclined at an angle of about forty-five degrees and are amply wide, valve chamber 20 being shown in section in Fig. 7, and the valve stem guide 9 for the inlet valve of cylinder 5 being seen in elevation. Each of these valve chambers contains two inlet valve seats 19, as seen in Fig. 1, which also shows a vertical section of the valve chamber 20 on the line 1-1 of Fig. 3.

The exhaust manifold 25 consists of a substantially straight but flaring tube parallel to the outer casing of the water jacket and communicating with exhaust valve seats 130

through passages 26, see Figs. 3 and 8. The relative arrangement of the inlet and exhaust manifolds on opposite sides of the valve stem guides 9 and below the valve seats is of importance in securing compactness, it being seen that these manifolds are fully within the water jacket, with water circulation entirely around them, and of ample area, without increasing the total width of the casting. In order to provide access to the valve seats and valves, bushings 11 are provided in which the spark plugs will be inserted, while the openings 12 in the cylinder heads are intended to receive pet-cocks, it being seen that the pet-cocks (or spark plugs, if desired) when properly screwed in will prevent any water from getting into the cylinder head. The bushings 11 being outside of the cover 8 can be removed without disturbing the water connections, so that a valve can be inserted or removed or ground on its seat.

30 is a cover removably fitted to the valve side of the casting to inclose the valve lifts, being secured by thumb-screw 47 threaded on a bolt 48.

The novel features of inlet and exhaust manifolds herein shown but not claimed, are claimed in my copending application Serial 30 No. 533,554, filed December 17, 1909, while the novel features relating to cooling are broadly claimed in my copending application Serial No. 600,854, filed January 5, 1911, while the novel features pertaining to 35 an inclosed combustion engine are claimed in my copending application Serial No. 759,628, filed April 8, 1913, as a division of said application Serial No. 600,854. While the specific form illustrated herein embodies 40 both inlet and exhaust valves on the same side of the cylinders, or what is sometimes termed the L-head construction, it will be understood that the invention is not restricted thereto as it may be embodied in 45 other forms such as the T-head and overhead constructions, except as limited to a specific construction by the appended claims.

Having thus described my invention, I declare that what I claim as new and desire 50 to secure by Letters Patent, is:—

1. An integral six cylinder combustion engine casting comprising three pairs of engine cylinders, a transverse admission passage between each pair of cylinders, a longitudinal passage intermediately connected to said transverse admission passages, and a passage from said longitudinal passage to each of said cylinders.

60 2. An integral six cylinder combustion engine casting comprising three spaced pairs of engine cylinders, a transverse admission passage in said space between each pair of cylinders, a longitudinal passage intermediately connected to said transverse admission passages, and a passage from

said longitudinal passage to each of said cylinders.

3. An integral six cylinder combustion engine casting comprising three pairs of engine cylinders, the cylinders of each pair being in contact vertically, a transverse admission passage between each pair of cylinders, a longitudinal passage intermediately connected to said transverse admission passages, and a passage from said longitudinal 70 passage to each of said cylinders.

4. An integral six cylinder combustion engine casting comprising three pairs of engine cylinders, a transverse admission passage between each pair of cylinders, a longitudinal passage having closed ends intermediately connected to said transverse admission passages and communicating with each cylinder at substantially equal distances from said transverse passages, an integral water jacket surrounding said cylinders and passages, and an exhaust passage formed integrally with said casting and having connection with each of said cylinders. 80

5. An integral engine casting comprising an external water jacket, six aligned cylinders each having an inlet, a single supply passage within the casting extending longitudinally of said cylinders and connecting 95 said inlets, and means connected within the casting intermediately to said longitudinal passage for equally supplying said cylinders with charge.

6. A casting for an integral six cylinder engine comprising a plurality of groups of cylinders, an external water jacket, an inlet pipe extending longitudinally on one side of and adjacent said cylinders and having a branch leading to each cylinder, and a supply branch between each group connected with said casting intermediately to said inlet pipe for equally supplying said cylinders with charge. 100

7. An integral engine casting comprising 110 an external water jacket, six aligned cylinders each having an overhang on one side for an inlet and an exhaust valve, a chamber for each valve, a single supply passage within the casting extending longitudinally and connecting said inlet chambers, means connected within the casting intermediately to said longitudinal passage for equally supplying said cylinders with charge, and an exhaust passage adjacent said supply passage connected to each of said exhaust chambers and opening through the water jacket at one end. 115

8. An integral engine casting comprising 120 six aligned cylinders each having an overhang on one side for an inlet and an exhaust valve, an inlet and an exhaust valve chamber below each overhang, a single supply passage extending longitudinally below and connecting said inlet chambers, a plu- 125

65 130

rality of transverse supply passages within the casting opening intermediately into said supply passage for equally supplying said cylinders with charges and an exhaust passage extending longitudinally adjacent said supply passage from one extreme exhaust valve chamber through the opposite end of said casting.

9. An integral engine casting comprising 10 six alined cylinders each having an overhang on one side for an inlet valve, inlet chambers below said overhangs common to each pair of cylinders, a single supply passage within the casting extending longitudinally adjacent said cylinders and connecting said inlet chambers, and a plurality of transverse supply passages opening through the side of said casting intermediately into said supply passage for equally 20 supplying said cylinders with charge.

10. An engine casting comprising six alined cylinders each having an overhang on one side for an inlet valve, a plurality of inlet valve chambers below said overhang, a 25 supply passage within the casting extending longitudinally of said cylinders between the extreme inlet chambers, a plurality of transverse supply passages opening from the side of said casting intermediately into said 30 supply passage for equally supplying said cylinders with charge, and an integral water jacket inclosing said cylinders, inlet passages, valve chambers and overhangs.

11. An engine casting comprising six alined cylinders each having an overhang on one side for an inlet valve, a plurality of valve chambers below said overhangs, a supply passage extending longitudinally of said cylinders between the extreme inlet 35 chambers, a plurality of transverse supply passages opening from the side of said casting intermediately into said supply passage, a water jacket open at the top inclosing said cylinders, inlet passages, valve chambers 40 and overhangs, in combination with a channeled removable cover for said water jacket, said cover having a water inlet from the jacket at one end and an outlet at the opposite end, and said water jacket having a 45 water inlet at the end distant from said cover inlet with intervening baffles for directing the flow of water upwardly of said cylinders and longitudinally over said cylinder heads.

12. A water jacketed engine casting comprising 55 six alined cylinders arranged in pairs having a common wall and integral heads, inlet passages for supplying said cylinders including a longitudinal passage with transverse branches between said pairs of 60 cylinders, a water jacket surrounding said cylinders and passages, a water inlet adjacent one end of said jacket and a water outlet adjacent the opposite end, and vertically disposed baffles between said cylinders and 65 said jacket coöperating with said common walled cylinders to direct the flow of water upwardly of said cylinders and longitudinally over said cylinder heads to said outlet.

13. An engine casting comprising six 70 alined cylinders each having an overhang on one side for an outlet and an exhaust valve, a plurality of inlet and exhaust valve chambers below said overhangs, a supply 75 passage within the casting extending longitudinally of said cylinders between the extreme inlet chambers, means connected within the casting intermediately to said supply passage for equally supplying said cylinders with charge, an exhaust passage extending 80 longitudinally below said overhang adjacent said supply passage from one extreme exhaust valve chamber through the opposite end of said casting, and valve stem guides between said inlet and exhaust passages. 85

14. An engine casting comprising six alined cylinders each having an overhang on one side for an inlet and an exhaust valve, a plurality of inlet and exhaust valve chambers below said overhangs, a supply passage 90 within the casting extending longitudinally of said cylinders between the extreme inlet chambers, a plurality of transverse supply passages opening from the side of said casting intermediately into said supply passage, an exhaust passage extending longitudinally adjacent said supply passage from one extreme exhaust valve chamber through the opposite end of said casting, and a water jacket having separated inlet and outlet openings inclosing said cylinders, supply 95 and exhaust passages. 100

In testimony whereof I affix my signature, in presence of two witnesses:

GUIDO FORNACA.

Witnesses:

GRATZ ALBAO.

It is hereby certified that in Letters Patent No. 1,190,255, granted July 4, 1916, upon the application of Guido Fornaca, of Turin, Italy, for an improvement in "Combustion-Engines," an error appears in the printed specification requiring correction as follows: Page 4, line 72, for the word "outlet" read *inlet*; and that the said Letters Patent should be read with this correction therein that the same may conform to the record of the case in the Patent Office.

Signed and sealed this 25th day of July, A. D., 1916.

[SEAL.]

F. W. H. CLAY,

Acting Commissioner of Patents.

Cl. 123—193.
